RAILWAY TRAFFIC CONTROLLING
APPARATUS

Charles W. Failor, Forest Hills, Pa., assignor to
The Union Switch & Signal Company, Swiss-
vale, Pa., a corporation of Pennsylvania

Application May 19, 1937, Serial No. 143,481

22 Claims. (Cl. 246—39)

My invention relates to railway traffic controlling apparatus, and particularly to automatic train control or cab signal systems of the coded continuous inductive type. More particularly, my present invention relates to the trackway portion of systems of this character.

One feature of my invention is the provision, in systems of this type, of means for controlling the energy supplied to the sections in the rear of an occupied section in such a manner that the train control apparatus carried on a train moving over the sections will assume the same restrictive condition throughout more than one section in the rear of an occupied section.

I shall describe several forms of apparatus embodying my invention, and shall then point out the novel features thereof in claims.

In the accompanying drawings, Fig. 1; Figs. 2A, and 2B, when placed end to end in the order named; and Figs. 3A and 3B, when placed end to end in the order named, are diagrammatic views illustrating the trackway apparatus for three-block, four-block, and five-block train control systems, respectively, and each embodying my invention. Fig. 4; Figs. 5A, and 5B, when placed end to end in the order named; and Figs. 6A, 6B, and 6C, when placed end to end in the order named, are diagrammatic views illustrating trackway portions of systems similar to those shown in Figs. 1, 2A—2B, and 3A—3B, respectively, but wherein line conductors have been substituted for certain relays, and each also embodying my invention. Figs. 7A and 7B, when placed end to end in the order named, is a diagrammatic view illustrating the system shown in Figs. 6A—6B—6C but wherein certain of the line conductors have been eliminated, and also embodying my invention. Fig. 8 is a chart showing various other ways in which the train control currents may be distributed to sections in the rear of an occupied section. Fig. 9 is a diagrammatic view illustrating the trackway apparatus for supplying the train control currents to sections in the rear of an occupied section as shown in diagram 1 of Fig. 8, and also embodying my invention.

Similar reference characters refer to similar parts in each of the several views.

Referring first to Fig. 1, the reference characters 1 and 2 designate the track rails of a stretch of railway track along which traffic normally moves in the direction indicated by the arrow. These rails are divided by insulated joints 3 to form a plurality of track sections 1T, 2T, 3T, etc. As here shown, each section is provided

with an alternating current track relay designated by the reference character TR with a prefix the same as the prefix in the reference character of the associated track section. Each track relay is provided with a winding 4 which is connected directly across the rails at one end of the section and with a winding 5 which is connected to a suitable source of alternating current energy the terminals of which are designated BX and CX. Each section is provided with a transformer designated by the reference character M with a prefix the same as the prefix of the reference character of the associated track section. Each transformer is provided with a winding 6 connected across the rails at the other end of the section and with a winding 7 which, as will be explained more in detail hereinafter, is at times supplied with uncoded alternating current and at other times is supplied with coded alternating current. As here shown, each section is provided with a direct current approach relay or control relay designated by the reference character AR with a prefix the same as the prefix of the reference character of the associated track section. Each relay AR is controlled by a front contact 8 of the associated track relay so that the relays AR will become energized or de-energized according as the associated track relay is energized or deenergized. Each section is provided with a direct current relay designated by the reference character H with a prefix the same as the prefix in the reference character of the associated track section. Each relay H is controlled by a front contact 11 of the associated track relay as well as by a front contact 12 of the track relay for the section next in advance. That is, each relay H will become deenergized whenever the associated track section or the section next in advance is occupied. For energizing the direct current relays AR and H, each section is provided with a source of direct current the terminals of which are designated B and C. Each section is provided with a coding relay designated by the reference character CT with a prefix the same as the prefix in the reference character of the associated track section. Each relay CT is provided with a contact 75, a contact 120, and a contact 180 which may, for example, operate respectively at 75, 120, or 180 times per minute. Each coding relay is directly connected to terminals BX and CX of the source of alternating current so that its contacts are operating continuously.

When the control relays AR are energized so that front point of contact 9 is closed, the sup-

ply circuit leading to the primary winding 7 of the associated transformer M is supplied with uncoded energy to maintain the associated track relay in its energized condition. When the relays 5 AR are released so that the back point of contact 9 is closed, the supply circuit leading to the winding 7 of the associated transformer M is connected to an operating circuit which is supplied with uncoded energy or is connected to 10 a control circuit to which is supplied coded energy of one rate or another depending upon the condition of the track relay and the relay H for the section next in advance.

As here shown, the section 4T is occupied by 15 a train K so that relays 4TR and 4H are both deenergized. With relay 4TR released, the apparatus is in condition to supply uncoded energy to section 3T whenever relay 3AR becomes released. The circuit for supplying uncoded energy to transformer 3M may be traced over a 20 path which passes from terminal BX through back point of contact 10 of relay 4TR, operating circuit for section 3T, back point of contact 9 of relay 3AR, the supply circuit for section 3T 25 and winding 7 of transformer 3M to terminal CX.

The releasing of relay 4TR also releases relay 3H so that, when relay 2AR becomes released, the section 2T will be supplied with coded energy interrupted at the rate of 75 times per minute.

30 The circuit for supplying coded energy to winding 7 of transformer 2M may be traced over a path which passes from terminal BX through contact 75 of coding relay 3CT, back point of contact 13 of relay 3H, control circuit for section 35 2T, front point of contact 10 of relay 3TR, operating circuit for section 2T, back point of contact 9 of relay 2AR, the supply circuit for section 2T and winding 7 of transformer 2M to terminal CX.

Since the energization of relay 2H is not disturbed by the train K, the section 1T will be 40 supplied with coded energy interrupted at the rate of 120 times per minute when relay 1AR becomes released. The circuit for supplying section 1T with coded energy interrupted at the rate 45 of 120 times per minute may be traced over a path which passes from terminal BX through contact 120 of coding relay 2CT, front point of contact 13 of relay 2H, control circuit for section 1T, front point of contact 10 of relay 2TR, operating circuit for section 1T, back point of contact 50 9 of relay 1AR, the supply circuit for section 1T and winding 7 of transformer 1M to terminal CX.

The usual locomotive carried train control 55 apparatus (not shown) is responsive to coded energy only. That is, the train control apparatus will assume a stop condition if no energy or uncoded energy is present in the rails and will assume successively less restrictive proceed conditions according as the coded energy is interrupted at the rate of 75 or 120 times per minute. A following train, therefore, passing over the stretch in the rear of train K will assume one of its proceed conditions in section 1T because 60 65 the rails of that section will be supplied with coded current interrupted at the rate of 120 times per minute. In section 2T, the train control apparatus on the following train will assume a more restrictive proceed condition because the rails of section 2T will be supplied with coded current interrupted at the rate of 75 times per minute, but when the following train traverses sections 3T or 4T, the train control apparatus 70 75 will assume a stop condition because the rails of section 3T will be supplied with uncoded energy

and no energy is present in the rails of section 4T due to the shunt of wheels and axles of train K.

Uncoded energy is supplied to the rails of the first section in the rear of an occupied section in order to provide a pickup circuit for the track relay of the rear section in the event that the rails of the rear section should be shunted and then the shunt removed. Under this condition, energy will be supplied to the rails of the rear section over back point of contact 10 of the track relay for the section in advance and back point of contact 9 of the associated approach or control relay. When the track relay becomes energized so that front point of contact 8 becomes 10 closed, the associated approach or control relay AR will, of course, become energized to supply energy to the track circuit over the front point of contact 9. In the event that the rails of the section are shunted and then the shunt removed 15 while that section is being supplied with coded energy, the first impulse of the code will pick up the track relay so that the associated approach relay will also become picked up to restore the track circuit to its normal condition.

Referring now to Figs. 2A and 2B which illustrate a four-block system, each section is provided with a direct current polarized relay designated by the reference character D with a prefix the same as the prefix in the reference character of the associated track section. Each section is also supplied with a direct current slow releasing relay designated by the reference character DP with a prefix the same as the prefix in the reference character of the associated track section. Each relay DP is controlled by a front contact 15 of the associated relay D, that is, each relay DP will become energized or deenergized according as the associated relay D is energized or deenergized. Each relay D is controlled by 20 the associated track relay and the track relay for the section next in advance as well as by the relay DP for the section next in advance in such a manner that the winding of the relay D is energized in the normal direction or in the reverse direction according as the relay DP for the section in advance is energized or deenergized provided that the associated section and the section in advance are both unoccupied. For example, the winding of relay 2D is provided with 25 a circuit which passes over a path from terminal B of a source of current through front point of contact 16 of relay 3DP, front contact 17 of relay 3TR, front contact 18 of relay 2TR, relay 2D, front contact 19 of winding of relay 2TR, 30 front contact 20 of relay 3TR, and front point of contact 21 of relay 3DP to terminal C of the source of current.

As here shown, the train K occupies the section 5T so that track relay 5TR is released. 35 With the apparatus in this condition, the rails of section 4T will be supplied with uncoded energy over back point of contact 10 of relay 5TR, operating circuit for section 4T, back point of contact 9 of relay 4AR and the supply circuit 40 for section 4T if section 4T becomes occupied by a following train. The releasing of relay 5TR also caused relay 4D to become released so that, if a following train occupies section 3T, the rails of that section will be supplied with coded energy 45 interrupted at the rate of 75 times per minute. The circuit for supplying coded energy to the rails of section 3T may be traced over a path which passes from terminal BX of a source of alternating current through contact 75 of coding 50

relay 4CT, back point of contact 22 of relay 4D, control circuit for section 3T, front point of contact 10 of relay 4TR, operating circuit for section 3T, back point of contact 9 of relay 3AR, supply circuit for section 3T, and winding 7 of transformer 3M to terminal CX of the source of alternating current. The opening of front contact 15 of relay 4D causes the contacts of relay 4DP to be released so that the winding of relay 3D is energized in the reverse direction. The circuit for relay 3D may be traced over a path which passes from terminal B of a source of current through back point of contact 16 of relay 4DP, front point of contact 20 of relay 4TR, front contact 19 of relay 3TR, winding of relay 3D, front contact 18 of relay 3TR, front contact 17 of relay 4TR, and back point of contact 21 of relay 4DP to terminal C of the source of current.

Since relay 3D is energized in the reverse direction, the rails of section 2T will be supplied with coded energy interrupted at the rate of 120 times per minute if that section becomes occupied by a following train. The circuit for supplying coded energy to the rails of section 2T may be traced over a path which passes from terminal BX of a source of alternating current through contact 120 of coding relay 3CT, reverse polar contact 23-24 of relay 3D, front point of contact 22 of relay 3D, control circuit for section 2T, front point of contact 10 of relay 3TR, operating circuit for section 2T, back point of contact 9 of relay 2AR, supply circuit for section 2T, and winding 7 of transformer 2M to terminal CX of the source of alternating current.

Relay 2D is energized in the normal direction over the previously traced circuit for this relay because relay 3DP is energized. Under this condition, the rails of section 1T will be supplied with coded energy interrupted at the rate of 180 times per minute if that section becomes occupied by a following train. The circuit for supplying coded energy to the rails of section 1T may be traced over a path which passes from terminal BX of a source of alternating current through contact 180 of coding relay 2CT, normal polar contact 23-25 of relay 2D, front point of contact 22 of relay 2D, control circuit for section 1T, front point of contact 10 of relay 2TR, operating circuit for section 1T, back point of contact 9 of relay 1AR, supply circuit for section 1T, and winding 7 of transformer 1M to terminal CX of the source of alternating current.

The train control apparatus carried on a following train traversing the sections in the rear of train K will, therefore, be caused to assume its least restrictive condition while occupying section 1T because that section is supplied with coded energy interrupted 180 times per minute. When the following train enters section 2T, the train control apparatus will be caused to assume a more restrictive condition because the rails of section 2T will be supplied with coded energy interrupted at the rate of 120 times per minute. When the following train enters section 3T, the train control apparatus will be caused to assume a still more restrictive condition because the rails of section 2T will be supplied with coded current interrupted at the rate of 75 times per minute. The train control apparatus on the following train will be caused to assume its stop condition in both sections 4T and 5T because uncoded energy will be supplied to the rails of section 4T and no energy will be present in the rails of section 5T.

Referring now to Figs. 3A and 3B, which illus-

trate a five-block train control system, all apparatus is controlled in a manner similar to that described for the apparatus shown in Figs. 2A and 2B except the control for the polarized relays D. Relay 2D, for example, is provided with a control circuit which passes over a path from terminal B of a source of current through front point of contact 27 of relay 4DP, front contact 28 of relay 3TR, front contact 29 of relay 2TR, winding of relay 2D, front contact 30 of relay 2TR, front contact 31 of relay 3TR, and front point of contact 32 of relay 4DP to terminal C of the source of current. When contacts 27 and 32 of relay 4DP are released they engage their back points of contact to thereby effect the supply of current of reverse relative polarity to the circuit of the winding of relay 2D. Relay 2D, therefore, will be energized in one direction or the other when sections 2T and 3T are both unoccupied according as the relay 4DP is energized or deenergized, respectively. Energization of the winding of relay 4DP is controlled by the neutral contact 15 of relay 4D, while energization of the winding of relay 4D is controlled by the track relays 4TR and 5TR in such manner that the winding of relay 4D is deenergized when either section 4T or 5T is occupied, but is energized when both of these sections are unoccupied. It will be seen, therefore, that the relay 2D will be energized in the reverse direction not only when section 4T is occupied but also when section 5T is occupied and that the relay 2D will be energized in the normal direction when sections 4T and 5T are both unoccupied. Each of the relays D is controlled in a manner similar to that described for the relay 2D.

A train K is indicated diagrammatically in the section 6T so that relay 6TR is released. Under this condition, if a following train enters section 5T, the rails of that section will be supplied with steady energy over a path which passes from terminal BX of a source of alternating current through back point of contact 10 of relay 6TR, operating circuit for section 5T, back point of contact 9 of relay 5AR, supply circuit for section 5T, and winding 7 of transformer 5M to terminal CX of the source of alternating current.

The releasing of relay 6TR also causes relay 5D to become released so that, if a following train enters section 4T, the rails of that section will be supplied with coded energy interrupted at the rate of 75 times per minute. The circuit for supplying coded energy to the rails of section 4T may be traced over a path which passes from terminal BX of a source of alternating current through contact 75 of coding relay 5CT, back point of contact 22 of relay 5D, control circuit for section 4T, front point of contact 10 of relay 5TR, back point of contact 9 of relay 4AR, and winding 7 of transformer 4M to terminal CX.

Relay 4D is energized in the reverse direction because relay 6DP is released. The circuit for relay 4D may be traced over a path which passes from terminal B through back point of contact 27 of relay 6DP, front contact 31 of relay 5TR, front contact 30 of relay 4TR, winding of relay 4D, front contact 28 of relay 4TR, front contact 28 of relay 5TR, and back point of contact 32 of relay 6DP to terminal C. Relay 4D being energized in the reverse direction will establish a circuit so that, if a following train enters section 3T, the rails of that section will be supplied with coded energy interrupted at the rate of 120 times per minute. The circuit for supplying coded current to the rails of section 3T may be

75

traced over a path which passes from terminal BX of a source of alternating current through contact 120 of relay 4CT, reverse polar contact 23-24 of relay 4D, front point of contact 22 of relay 4D, control circuit for section 3T, front point of contact 10 of relay 4TR, operating circuit for section 3T, back point of contact 9 of relay 3AR, supply circuit for section 3T, and winding 7 of transformer 3M to terminal CX of the source of alternating current.

Relay 3D is energized in the reverse direction because relay 5DP is released. The circuit for relay 3D may be traced over a path similar to the circuit previously traced for relay 4D. When 15 relay 3D is energized in the reverse direction, the rails of section 2T will also be supplied with coded energy interrupted at the rate of 120 times per minute if that section should become occupied by a following train. The circuit for supplying coded 20 energy to the rails of section 2T is similar to the circuit previously traced for supplying coded energy to the rails of section 3T.

The rails of section 1T, if that section becomes occupied by a following train, will be supplied 25 with coded energy interrupted at the rate of 180 times per minute because relay 2D is energized in the normal direction over its previously traced circuit. The circuit for supplying coded energy to the rails of section 1T may be traced over a 30 path which passes from terminal BX of a source of alternating current through contact 180 of coding relay 2CT, normal polar contact 23-25 of relay 2D, front point of contact 22 of relay 2D, control circuit for section 1T, front point of 35 contact 10 of relay 2TR, operating circuit for section 1T, back point of contact 9 of relay 1AR, supply circuit for section 1T, and winding 7 of transformer 1M to terminal CX.

The train control apparatus on a following train 40 traversing the sections in the rear of train K will assume its least restrictive condition while occupying section 1T because the rails of that section will be supplied with coded energy interrupted at the rate of 180 times per minute. As 45 the following train traverses sections 2T and 3T, the train control apparatus will be caused to assume the same less restrictive condition in both sections because the rails of these two sections will be supplied with coded energy interrupted at the rate of 120 times per minute. In section 4T 50 the train control apparatus on the following train will be caused to assume a still more restrictive condition because the rails of that section will be supplied with coded energy interrupted at the rate of 75 times per minute. While a following train traverses sections 5T and 6T, the train control apparatus will be caused to assume its stop condition because the rails of the former section will be supplied with uncoded energy and 55 the rails of the latter section will not be supplied with energy due to the shunting action of the wheels and axles of the train K.

Referring next to Fig. 4, the apparatus shown 60 therein will govern the train control apparatus in the same manner as the system shown in Fig. 1, but in the system shown in Fig. 4 line conductors have been substituted for the approach relays AR and the relays H.

Track relay 4TR is released because section 4T 65 is occupied by a train K so that uncoded energy is supplied over back points of contacts 44 and 45 of relay 4TR through the supply circuit for section 3T to the primary winding 1 of transformer 3M and thus to the rails of section 3T. 70 The train control apparatus on a following train

occupying section 3T will, therefore, assume a stop condition.

If a following train enters section 2T so that uncoded energy is disconnected from wires 37 and 38, the train control apparatus on the following train will receive a restrictive proceed indication because the rails of section 2T will then be supplied with only coded energy interrupted at the rate of 75 times per minute. Coded energy will be supplied to the rails of section 2T from secondary winding 41 of transformer 3N over the control circuit for section 2T which circuit includes wires 42 and 43 and front points of contacts 44 and 45 of track relay 3TR. The coded energy will be supplied to primary winding 46 15 of transformer 3N over contact 75 of coding relay 4CT and back point of contact 47 of relay 4TR.

The train control apparatus on a following train occupying section 1T will be caused to assume a less restrictive proceed indication because uncoded energy will be disconnected from wires 37 and 38 of section 1T so that only coded energy interrupted at the rate of 120 times per minute will be supplied to the rails of section 1T. 20 Primary winding 46 of transformer 2N is supplied with coded energy at the rate of 120 times per minute over front contact 120 of coding relay 3CT and front point of contact 47 of relay 3TR so that secondary winding 41 of transformer 2N 30 will supply coded energy to transformer 1M over wires 42 and 43 which form the control circuit of section 2T and front points of contacts 44 and 45 of relay 2TR.

It will be noted that, under normal conditions, 35 that is, when the sections are unoccupied, the rails of each section are supplied with coded energy simultaneously with uncoded energy and that, when a section becomes occupied, the uncoded energy will be disconnected and either coded energy or uncoded energy will be supplied to the rails in accordance with traffic conditions in advance. The train control apparatus is so arranged that it will not assume a proceed condition if coded energy is supplied to the rails 40 simultaneously with uncoded energy. That is, when uncoded energy is present in the rails, the train control apparatus will assume the stop condition even though coded energy is also present.

Referring next to Figs. 5A and 5B, the apparatus shown therein will function in a manner similar to that described for the apparatus shown in Figs. 2A and 2B, but in the present figures line conductors have been substituted for relays AR, D, and DP.

The presence of the train K in section 5T 55 causes the relay 5TR to be released to open the front points of its contacts 44 and 45 so that the supply of coded energy to section 4T is disconnected.

Coded energy interrupted at the rate of 75 times per minute is supplied to section 3T from secondary winding 49 of transformer 5P through back points of contacts 50 and 51 of relay 5TR, wires 52 and 53 which form the control circuit of section 4T, and front points of contacts 44 and 45 of track relay 4TR. Primary winding 54 of transformer 5P is supplied with coded energy by contact 75 of coding relay 5CT.

Coded energy interrupted at the rate of 120 70 times per minute is supplied to section 2T by secondary winding 55 of transformer 5S, wires 56 and 57 of section 4T, front points of contacts 58 and 59 of relay 4TR, wires 52 and 53 of

section 3T which form the control circuit for section 2T, front points of contacts 44 and 45 of relay 3TR, supply circuit for section 2T, and transformer 2M. Primary winding 60 of transformer 5S is supplied with coded energy by a circuit which includes contact 120 of coding relay 5CT and back point of contact 61 of relay 5TR.

The rails of section 1T are supplied with coded energy interrupted at the rate of 180 times per minute because relay 4TR is energized. Primary winding 60 of transformer 4S is supplied with coded energy by a circuit which includes contact 180 of coding relay 4CT and front point of contact 61 of relay 4TR. Secondary winding 55 of transformer 4S is, therefore, supplying coded energy interrupted at the rate of 180 times per minute to transformer 1M over wires 56 and 57 of section 3T, front points of contacts 58 and 59 of track relay 3TR, wires 52 and 53 of section 2T which form the control circuit for section 1T, front points of contacts 44 and 45 of relay 2TR, supply circuit for section 1T, and transformer 1M.

It follows, therefore, that if a following train moves over sections 1T, 2T, and 3T to release the track relays associated with such sections, the opening of the front points of contacts 39 and 40 of these relays will disconnect uncoded energy from the associated transformer M so that these sections will be supplied with coded energy only. Consequently, the train control apparatus on the following train will be caused to assume a proceed condition to correspond to the character of the coded current supplied thereto. The train control apparatus on the following train will, of course, assume a stop condition in sections 4T and 5T because no energy is present in the rails of the latter section and uncoded energy is supplied to the former section over back points of contacts 44 and 45 of relay 5TR.

Referring now to Figs. 6A, 6B, and 6C, the apparatus shown therein will function in a manner similar to that described for the apparatus shown in Figs. 3A and 3B, but in the present figures line conductors have been substituted for relays AR, D, and DP.

The opening of front points of contacts 44 and 45 of relay 6TR by the presence of train K in section 6T will disconnect coded energy from the rails of section 5T so that the train control apparatus on a following train occupying section 5T will be caused to assume a stop condition.

The rails of section 4T are supplied with coded energy interrupted at the rate of 75 times per minute so that, when a following train enters section 4T to open front contacts 39 and 40 of relay 4TR, the train control apparatus on such following train will be caused to assume its most restrictive proceed condition. Primary winding 54 of transformer 6P is supplied with coded energy over contact 75 of coding relay 6CT so that secondary winding 49 of transformer 6P supplies coded energy interrupted at the rate of 75 times per minute over back points of contacts 50 and 51 of relay 6TR, wires 52 and 53 of section 5T which form the control circuit of section 4T, front points of contacts 44 and 45 of relay 5TR, supply circuit for section 4T, and transformer 4M.

Since relay 6TR is released, the rails of section 3T are supplied by coded energy interrupted at the rate of 120 times per minute so that, when a following train enters section 3T, the opening of front contacts 39 and 40 of relay 3TR will cause the train control apparatus on

the following train to assume a less restrictive proceed indication. The rails of section 3T are supplied with coded energy from secondary winding 62 of transformer 6Q over back points of contacts 63 and 64 of track relay 6TR, wires 65 and 66 of section 5T, front points of contacts 50 and 51 of relay 5TR, wires 52 and 53 of section 4T which form the control circuit for section 3T, front points of contacts 44 and 45 of relay 4TR, supply circuit for section 3T, and transformer 3M. Primary winding 67 of transformer 6Q is supplied with coded energy over contact 120 of coding relay 6CT.

The rails of section 2T are also supplied with coded energy interrupted at the rate of 120 times per minute so that, when this section becomes occupied by a following train to open contacts 39 and 40 of relay 2TR, the train control apparatus on such following train will be caused to assume the same restrictive condition as when occupying section 3T. Primary winding 60 of transformer 6S is supplied with coded current over a circuit which includes contact 120 of coding relay 6CT and back point of contact 61 of relay 6TR so that secondary winding 55 of transformer 6S is supplying coded energy over wires 56 and 57 of section 5T, front points of contacts 63 and 64 of relay 5TR, wires 65 and 66 of section 4T, front points of contacts 50 and 51 of relay 4TR, wires 52 and 53 of section 3T which form the control circuit for section 2T, front points of contacts 44 and 45 of relay 3TR, supply circuit for section 2T, and transformer 2M.

The rails of section 1T are supplied with coded energy interrupted at the rate of 180 times per minute so that, when a following train occupies that section to disconnect uncoded energy from the rails, the train control apparatus will assume its normal proceed condition. Primary winding 60 of transformer 5S is supplied with coded energy by a circuit which includes contact 180 of coding relay 5CT and front point of contact 61 of relay 5TR so that secondary winding 55 of transformer 5S is supplying energy to the rails of section 1T over wires 56 and 57 of section 4T, front points of contacts 63 and 64 of relay 4TR, wires 65 and 66 of section 3T, front points of contacts 50 and 51 of relay 3TR, wires 52 and 53 of section 2T which form the control circuit for section 1T, front points of contacts 44 and 45 of relay 2TR, supply circuit for section 1T, and transformer 1M.

Referring now to Figs. 7A and 7B, the apparatus shown herein is similar to that shown in Figs. 6A, 6B, and 6C, but in the present figures the number of line conductors have been reduced.

The releasing of relay 6TR by the train K supplies uncoded energy over back point of contact 70 of relay 6TR to the supply circuit leading to primary winding 71 of autotransformer 5A so that secondary winding 72 of autotransformer 5A will supply uncoded energy to the rails of section 5T over back point of contact 73 of track relay 5TR when section 5T becomes occupied by a following train.

When section 4T becomes occupied by a following train to open front point of contact 73 and to close back point of contact 73 of relay 4TR, secondary winding 72 of autotransformer 4A will be connected to transformer 4M so that the rails of the section will be supplied with coded energy interrupted at the rate of 75 times per minute. The circuit for supplying coded energy to primary winding 71 of autotransformer 4A passes over a path from terminal BX of a source

of alternating current through contact 75 of coding relay 6CT, back point of contact 74 of relay 6TR, wire 69 of section 5T which forms the control circuit of section 4T, front point of contact 70 of relay 5TR, wire 76 which forms the supply circuit of section 4T, and primary winding 71 to terminal CX of the source of alternating current.

When section 3T becomes occupied by a following train, the rails of that section will be supplied with coded energy interrupted at the rate of 120 times per minute by secondary winding 72 of autotransformer 3A. The circuit for supplying coded energy to primary winding 71 of autotransformer 3A may be traced from terminal BX of the source of alternating current through front point of contact 120 of coding relay 6CT, back point of contact 77 of relay 6TR, wire 78 of section 5T, front point of contact 14 of relay 5TR, wire 69 of section 4T which forms the control circuit for section 3T, front point of contact 70 of relay 4TR, wire 76 which forms the supply circuit of section 3T, and primary winding 71 of autotransformer 3A to terminal CX of the source of alternating current.

When section 2T becomes occupied by a following train, secondary winding 72 of autotransformer 2A will supply coded energy also interrupted at the rate of 120 times per minute to the rails of section 2T. The circuit for supplying coded energy to primary winding 71 of autotransformer 2A may be traced from terminal BX of the source of alternating current through back point of contact 120 of coding relay 6CT, back point of contact 79 of relay 6TR, wire 80 of section 5T, front point of contact 77 of relay 5TR, wire 78 of section 4T, front point of contact 74 of relay 4TR, wire 69 of section 3T which forms the control circuit for section 2T, front point of contact 70 of relay 3TR, wire 76 which forms the supply circuit of section 2T, and primary winding 71 of autotransformer 2A to terminal CX of the source of alternating current.

When section 1T becomes occupied by a following train, the rails of that section will be supplied with coded energy interrupted at the rate of 180 times per minute through transformer 1M and autotransformer (not shown) for the section 1T by a circuit which includes contact 180 of coding relay 5CT, front point of contact 79 of relay 5TR, wire 80 of section 4T, front point of contact 77 of relay 4TR, wire 78 of section 3T, front point of contact 74 of relay 3TR, wire 69 of section 2T which forms the control circuit for section 1T, front point of contact 70 of relay 2TR, and wire 76 which forms the supply circuit of section 1T.

Referring to Fig. 8, I have shown therein six different charts illustrating various combinations of codes supplied to sections in the rear of an occupied section. Except for the chart identified as No. 1 no attempt has been made to show detailed circuits for supplying the energy to the sections in the rear of an occupied section as called for by the various combinations shown in these charts because it is felt that in view of the relatively large number of circuits already shown in detail it will be readily apparent to any one skilled in the art how these various circuits might be modified to provide the controls indicated in the charts.

Fig. 9 shows detailed apparatus for supplying coded energy interrupted at the rate of 75 times per minute to the first and second sections in the rear of an occupied section and for supplying

coded energy interrupted at the rate of 180 times per minute to the rails of the third section in the rear of an occupied section as called for by chart 1. The presence of the train K in section 4T releases control relays 3H and 4H because contacts 11 and 12 of relay 4TR are open. Since back points of contacts 13 of control relays 3H and 4H are both closed, the rails of sections 2T and 3T will both be supplied with coded energy interrupted at the rate of 75 times per minute when those sections become occupied by a following train to close back points of contacts 9 of relays 2AR and 3AR.

Since control relay 2H is energized over front points of contacts 11 and 12 of relays 2TR and 3TR, the rails of section 1T will be supplied with coded energy interrupted at the rate of 180 times per minute over front point of contact 13 of relay 2H, control circuit for section 1T, back point of contact 9 of relay 1AR and the supply circuit for section 1T when relay 1AR becomes released by the following train. The train control apparatus on a train traversing the sections in the rear of train K will, therefore, assume its normal proceed condition in section 1T and will assume its most restrictive proceed condition in both sections 2T and 3T. If the following train enters section 4T, the absence of energy in the rails of that section will cause the train control apparatus on the following train to assume its stop condition.

My present invention provides that train control apparatus will assume a restrictive condition throughout more than one section in the rear of an occupied section and is, therefore, useful when the braking distance required for safe operation is greater than the length of the track sections.

Although I have herein shown and described only several forms of apparatus embodying my invention, it is understood that various changes and modifications may be made therein within the scope of the appended claims without departing from the spirit and scope of my invention.

Having thus described my invention, what I claim is:

1. In a coded track circuit system for train control, a forward and a rear as well as an intermediate section of railway track, a track relay for the rear section receiving energy from the rails of the associated section, means effective when said track relay is energized to supply energy to the rails of the rear section to maintain such track relay energized when said rear section is unoccupied, a control relay, means for energizing said control relay only if the forward and intermediate sections are both unoccupied, means effective when the track relay of said rear section is released and the intermediate section is occupied to supply the rails of the rear section with uncoded energy, and means effective when the track relay of said rear section is released and the intermediate section is unoccupied to supply the rails of the rear section with coded energy of one characteristic or another according as said control relay is energized or deenergized.

2. In a coded track circuit system for train control, a rear and an intermediate as well as a forward section of railway track; a first, a second, and a third track relay receiving energy from the rails of said sections respectively; a circuit including a front contact of said first relay for supplying energy to the rails of the rear section

to maintain the first relay energized when the rear section is unoccupied, a circuit including a back contact of said second relay for supplying the rails of the rear section with uncoded energy, 5 a circuit including a front contact of said second relay and a front contact of said third relay for supplying the rails of the rear section with coded energy of one characteristic, and a circuit including a front contact of the second relay and 10 a back contact of the third relay for supplying the rails of the rear section with coded energy of another characteristic.

3. In a coded track circuit system for train control; a stretch of railway track divided into 15 first, second, third, and fourth track sections; a track relay receiving energy from the rails of the first track section, means effective when said track relay is energized to supply energy to the rails of the first section to maintain said track 20 relay energized when the section is unoccupied, a polarized control relay, means effective when said second and third sections are unoccupied to energize said control relay in one direction or another according as the fourth section is occupied 25 or unoccupied respectively, and means effective when said track relay is released and the second section is unoccupied to supply the rails of the first section with coded energy of one of three different characteristics according as said control 30 relay is deenergized or is energized in one direction or the other respectively.

4. In a coded track circuit system for train control; a stretch of railway track divided into first, second, third, and fourth track sections; 35 a first, a second, a third, and a fourth track relay receiving energy from the rails of said sections respectively; a circuit including a front contact of said first relay for supplying energy to the rails of the first section to maintain the first 40 relay energized when the first section is unoccupied, a circuit including a back contact of said second relay for supplying uncoded energy to the rails of the first section, a circuit including a front contact of said second relay and a back contact of said third relay for supplying coded 45 energy of one characteristic to the rails of the first section, a circuit including a front contact of said second relay and a front contact of said third relay as well as a front contact of said fourth relay for supplying coded energy of another characteristic to the rails of the first section, a circuit including a front contact of said second relay and a front contact of said third relay as well as a front contact of 50 said fourth relay and a back contact of said fifth relay for also supplying coded energy of said other characteristic to the rails of said first section; and a circuit including a front contact of each of said second, third, fourth, and fifth relays 55 for supplying coded energy of a different characteristic to the rails of said first section.

5. In a coded track circuit system for train control; a stretch of railway track divided into 60 first, second, third, fourth, and fifth track sections; a track relay receiving energy from the rails of the first track section, means effective when said track relay is energized to supply energy to the rails of the first section to maintain 65 said track relay energized when the section is unoccupied, a polarized control relay, means effective when said second and third sections are unoccupied to energize said control relay in one direction or another according as said fourth 70 and said fifth sections are both unoccupied or either is occupied, and means effective when said track relay is released and the second section is unoccupied to supply the rails of the first section with coded energy of one of three different characteristics according as said polarized relay 75

is deenergized or is energized in one direction or the other respectively.

6. In a coded track circuit system for train control; a stretch of railway track divided into first, second, third, fourth, and fifth track sections; a first, a second, a third, a fourth, and a fifth track relay receiving energy from the rails of said sections respectively, a circuit including a front contact of said first relay for supplying energy to the rails of the first section to maintain said first relay energized when the first section is unoccupied, a circuit including a back contact of said second relay for supplying uncoded energy to the rails of the first section, a circuit including a front contact of said second relay and a back contact of said third relay for supplying coded energy of a particular characteristic to the rails of the first section, a circuit including a front contact of said second relay and a front contact of said third relay as well as a back contact of said fourth relay for supplying coded energy of another characteristic to the rails of the first section, a circuit including a front contact of said second relay and a front contact of said third relay as well as a front contact of 10 said fourth relay and a back contact of said fifth relay for also supplying coded energy of said other characteristic to the rails of said first section; and a circuit including a front contact of each of said second, third, fourth, and fifth relays 15 for supplying coded energy of a different characteristic to the rails of said first section.

7. In a coded track circuit system for train control, a rear and an intermediate as well as a forward section of railway track, a track relay 20 for the rear section receiving energy from the rails of that section, means effective when said track relay is in its picked up condition to supply energy to the rails of the rear section to maintain the associated track relay in such condition, 25 a control relay, means for energizing said control relay only if the forward and intermediate sections are both unoccupied, a circuit including a front contact of said control relay for supplying coded energy of one character to the rails of the rear section when said track relay is released, and a circuit including a back contact of said control relay for supplying coded energy of another character to the rails of the rear section 30 when said track relay is released.

8. In a coded railway traffic controlling system, in combination, a stretch of railway track divided into a plurality of successive block sections each having a track relay connected across the track rails adjacent the entrance end of the block section, said track relay being energized when said block section is unoccupied and being deenergized when said section is occupied, each track relay controlling a control relay which controls a supply circuit through which current may be 35 supplied to the track rails of said block section at a point adjacent the exit end thereof, said control relay being operative when the track relay of said section is energized to supply energy to said supply circuit and thereby to the track 40 rails of said section to maintain the track relay energized, said control relay being operative when said track relay is deenergized to connect said supply circuit to an operating circuit, means controlled by the track relay of the adjacent block 45 section in advance of each section for supplying current to said operating circuit or for connecting said operating circuit to a control circuit, means for supplying coded energy of a plurality of different characters, and means controlled by the 50

track relay of the block section second in advance of each section for selectively supplying coded energy of one character or another from said coded energy supply means to said control circuit.

9. In a coded railway traffic controlling system, in combination, a stretch of railway track divided into a plurality of successive block sections each having a track relay connected across the track rails adjacent the entrance end of the block section, said track relay being energized when said block section is unoccupied and being deenergized when said section is occupied, each track relay controlling a control relay which controls a supply circuit through which current may be supplied to the track rails of said block section at a point adjacent the exit end thereof, said control relay being operative when the track relay of said section is energized to supply energy to said supply circuit and thereby to the track rails of said section to maintain the track relay energized, said control relay being operative when said track relay is deenergized to connect said supply circuit to an operating circuit, means controlled by the track relay of the adjacent block section in advance of each section for supplying current to said operating circuit or for connecting said operating circuit to a control circuit, means for supplying coded energy of a plurality of different characters, each section having a polarized relay effective to supply coded energy from said coded energy supply means to the control circuit for the adjacent section in the rear according as said relay is deenergized or is energized in one direction or the other respectively, and means controlled by the track relay of the adjacent block section in advance of the section with which said polarized relay is associated for supplying energy to said polarized relay.

10. In a coded railway traffic controlling system, in combination, a stretch of railway track divided into a plurality of successive block sections each having a track relay connected across the track rails adjacent the entrance end of the block section, said track relay being energized when said block section is unoccupied and being deenergized when said section is occupied, each track relay controlling a control relay which controls a supply circuit through which current may be supplied to the track rails of said block section at a point adjacent the exit end thereof, said control relay being operative when the track relay of said section is energized to supply energy to said supply circuit and thereby to the track rails of said section to maintain the track relay energized, said control relay being operative when said track relay is deenergized to connect said supply circuit to an operating circuit, means controlled by the track relay of the adjacent block section in advance of each section for supplying current to said operating circuit or for connecting said operating circuit to a control circuit, means for supplying coded energy of a plurality of different characters, each section having a polarized relay effective to supply coded energy from said coded energy supply means to the control circuit for the adjacent section in the rear according as said relay is deenergized or is energized in one direction or the other respectively, and means controlled by the track relay of the second block section in advance of the section with which said polarized relay is associated for controlling the

polarity of the current supplied to said polarized relay.

11. In a coded railway traffic controlling system, in combination, a stretch of railway track divided into a plurality of successive block sections each having a track relay connected across the track rails adjacent the entrance end of the block section, said track relay being energized when said block section is unoccupied and being deenergized when said section is occupied, each track relay controlling control relay which controls a supply circuit through which current may be supplied to the track rails of said block section at a point adjacent the exit end thereof, said control relay being operative when the track relay of said section is energized to supply energy to said supply circuit and thereby to the track rails of said section to maintain the track relay energized, said control relay being operative when said track relay is deenergized to connect said supply circuit to an operating circuit, means controlled by the track relay of the adjacent block section in advance of each section for supplying current to said operating circuit or for connecting said operating circuit to a control circuit, means for supplying coded energy of a plurality of different characters, each section having a polarized relay effective to supply coded energy from said coded energy supply means to the control circuit for the adjacent section in the rear according as said relay is deenergized or is energized in one direction or the other respectively, and means for each polarized relay controlled by the track relay of a block section farther in advance of the section with which said polarized relay is associated than the adjacent block section for controlling the polarity of the current supplied to said polarized relay.

12. In a coded railway traffic controlling system, in combination, a stretch of railway track 40 divided into a plurality of successive block sections each having a track relay connected across the track rails adjacent the entrance end of the block section, said track relay being energized when said block section is unoccupied and being 45 deenergized when said section is occupied, a control relay controlled by said track relay and controlling a supply circuit through which current may be supplied to the track rails of said block section at a point adjacent the exit end thereof, 50 said control relay being operative when the track relay of said section is energized to supply energy to said supply circuit and thereby to the track rails of said section to maintain the track relay energized, said control relay being operative when 55 said track relay is deenergized to connect said supply circuit to an operating circuit, means controlled by the track relay of the adjacent block section in advance of each section for supplying current to the operating circuit for each section 60 or for connecting said operating circuit to a control circuit, means for supplying coded energy of a plurality of different characters, and means controlled by the track relays of the two adjacent sections in advance of each section for selectively supplying coded energy of one character 65 or another from said coded energy supply means to the control circuit for such section.

13. In a coded railway traffic controlling system, in combination, a stretch of railway track divided into a plurality of successive block sections each having a track relay connected across the track rails adjacent the entrance end of the block section, said track relay being energized when said block section is unoccupied and being 75

- deenergized when said section is occupied, said track relay being operative when and only when energized to supply current to said track rails at a point adjacent the exit end of the block 5 section to maintain itself energized, each section having associated therewith a supply circuit through which current may also be supplied to the track rails of said block section at a point adjacent the exit end thereof, each section also 10 having associated therewith means controlled by the track relay of the adjacent block section in advance for connecting said supply circuit to a source of current or to a control circuit, and means for each section controlled by the track 15 relay of the second block section in advance of such section for supplying coded energy of one character or another to the control circuit for such section according as said second block section in advance is occupied or unoccupied.
- 20 14. In a coded railway traffic controlling system, in combination, a stretch of railway track divided into a plurality of successive block sections including a first, a second and a third section, each of said sections having a track relay 25 connected across the track rails thereof, each of said block sections having associated therewith a supply circuit through which current may be supplied to the track rails of such section, the track relay associated with said second block section being operative according as said block section is occupied or unoccupied to connect the supply circuit of the first block section to a source of uncoded current or to a control circuit, and means other than the track relay associated with the said second block section and controlled by the track relay of the third block 30 section according as said section is occupied or unoccupied to effect the supply of coded current of one character or another to said control circuit.
- 40 15. In a coded railway traffic controlling system, in combination, a stretch of railway track divided into a plurality of successive block sections, each of said sections having a track relay 45 connected across the track rails thereof, each of said track relays having associated therewith a coded current supply device capable of supplying coded current of a plurality of different characters, each of said block sections having associated therewith a supply circuit through which current may be supplied to the track rails of such section, the track relay of each section being operative when said section is unoccupied to connect the supply circuit of the adjacent section 50 in the rear to a control circuit associated with such track relay and being operative when said section is occupied to disconnect said supply circuit from said control circuit, each of said track relays having associated therewith a polarized 55 relay operative according as said relay is deenergized or is energized in one direction or the other to selectively control the supply of coded current from the associated current supply device to the control circuit associated with said track relay, each track relay controlling a circuit independent of the track rails of the adjacent section in the rear for supplying current to the polarized 60 relay associated with the track relay of the adjacent section in the rear.
- 65 16. In a coded railway traffic controlling system, in combination, a stretch of railway track divided into a plurality of successive block sections each having a track relay connected across the rails thereof adjacent the entrance end of the section, each track relay being energized when 70
- 75 the associated block section is unoccupied and being deenergized when such section is occupied, means for each section operative when and only when the track relay for such section is energized to supply current to the track rails of such section at a point adjacent the exit end thereof to thereby maintain the relay energized, each block section having a supply circuit through which current may be supplied to the track rails of such section at a point adjacent the exit end of the section, each section also having associated therewith a second circuit other than the track rails of the adjacent block section in advance and extending at least to the track relay associated with the block section second in advance, 10 said second circuit being jointly controlled by the track relays of the adjacent and the second section in advance, and means for each section including such second circuit for effecting the supply of coded energy of one character or another to the supply circuit for such section.
- 15 17. In a coded railway traffic controlling system, in combination, a stretch of railway track divided into a plurality of successive block sections, each of such sections having a track relay 20 connected across the track rails thereof, each of said block sections having associated therewith a control relay operative according as said relay is energized or deenergized to supply coded energy of one character or another to a circuit through which current may be supplied to the track rails of the adjacent block section in the rear, each such control relay being energized by current supplied over a second circuit independent of the track rails of the section with which said control relay is associated, each such second circuit extending from the control relay at least to the track relay of the adjacent block section in advance of that with which the said control relay is associated and being controlled by traffic conditions in such adjacent section in advance.
- 25 18. In a coded railway traffic controlling system, in combination, a stretch of railway track divided into a plurality of successive block sections each having a track relay energized by current supplied over the track rails of such section, each track relay having associated therewith a coding device capable of supplying coded current of a plurality of different characters and a control relay operating according as it is energized or deenergized to establish circuits through which coded current of one or another of the characters supplied by the associated coding device may be supplied to the track rails of the adjacent section in the rear, each such control 30 relay being energized by current supplied over a circuit including a conductor other than one of the track rails of the track stretch and extending at least to the track relay of the adjacent section in advance of that with which the said control 35 relay is associated, the circuit for energizing each control relay being controlled by the track relay of the adjacent section in advance of the section with which the said control relay is associated.
- 40 19. In a coded railway traffic controlling system, in combination, a stretch of railway track divided into a plurality of successive block sections, each of said sections having a track relay energized by current supplied over the track rails of such section, each track relay having associated therewith a polarized control relay, each of said polarized control relays being operative according as said relay is deenergized or is energized with current of one relative polarity or the other to effect the supply of coded energy of one 45
- 50
- 55
- 60
- 65
- 70
- 75

- of three different characteristics to a circuit through which current may be supplied to the track rails of the adjacent block section in the rear, each control relay being energized by current supplied over a circuit including a conductor other than one of the track rails of the track stretch and extending at least to the track relay of the adjacent block section in advance of that with which the said control relay is associated, 5 the supply of current to the circuit for energizing the control relay associated with each section being controlled by the track relay of the adjacent block section in advance of that with which said control relay is associated, the polarity of 10 the current supplied to the circuit for energizing the control relay associated with each section being controlled by the track relay of a section farther in advance than the adjacent section in advance. 15
20. In a coded railway traffic controlling system, in combination, a stretch of railway track divided into a plurality of successive block sections, each of said sections having a track relay energized by current supplied over the track rails 25 of such section, each track relay having associated therewith a polarized control relay and a coding device capable of supplying coded current of a plurality of different characters, each of said control relays being operative to effect the supply of coded energy of one of three different characters supplied by the associated coding device according as said relay is deenergized or is energized with current of one relative polarity or the other to a circuit through which current may 30 be supplied to the track rails of the adjacent section in the rear, each control relay being energized by current supplied over a circuit including a conductor other than one of the track rails of the track stretch and extending to the track relay 35 of the adjacent block section in advance of that with which the said control relay is associated, the supply of current to the circuit for energizing the control relay associated with each section being controlled by the track relay of the adjacent block section in advance of that with which the said control relay is associated, the polarity of the current supplied to the circuit for energizing the control relay associated with each section being controlled by the track relay of a section 40 farther in advance than the adjacent section in advance. 45
21. In a coded railway traffic controlling system, in combination, a stretch of railway track divided into a plurality of successive block sections, each section having a track relay energized from the track rails of said section and having a supply circuit through which current may be supplied to the track rails of such section, each section having associated therewith a coding device capable of supplying coded current of a plurality of different characters, each section also having a control circuit through which coded current supplied by the coding device of a section in advance 50 may be supplied to the track rails of a section in the rear, the track relay for each section being operative according as it is energized or deenergized to establish circuits through which coded current of one character or another may be supplied from the associated coding device to the control circuit of a section in the rear, the track relay of each section being operative when deenergized to connect the supply circuit of the adjacent section in the rear to a source of uncoded current and being operative when energized to connect the supply circuit of the adjacent section in the rear to the control circuit of a section in 55 advance of such adjacent section in the rear. 60
22. In a coded railway traffic controlling system, in combination, a stretch of railway track divided into a plurality of successive block sections, each section having a track relay energized from the track rails of said section and having a supply circuit through which current may be supplied to the track rails of such section, each section having associated therewith a coding device capable of supplying coded current of a plurality of different characters, each section also having a control circuit through which coded current supplied by the coding device of a section in advance 65 may be supplied to the track rails of a section in the rear, the track relay for each section being operative according as it is energized or deenergized to establish circuits through which coded current of one character or another may be supplied from the associated coding device to the control circuit of a section in the rear, the track relay of each section controlling means for establishing connection between the supply circuit of the adjacent section in the rear and the control circuit of a section in advance of such adjacent section in the rear. 70
